Patented Sept. 14, 1926.

UNITED STATES PATENT OFFICE.

STEPHEN L. MORGAN, OF SKANEATELES, NEW YORK.

LOCK.

Application filed April 26, 1924. Serial No. 709,120.

The invention relates to locks of the permutation class applied to the operating mechanism of an automobile or other motor vehicle and serving to prevent unauthorized movement of the same.

The object of the invention is to provide a reliable lock operable from the instrument board of the car and acting directly upon the transmission mechanism thereof to hold the latter immovably in the inoperative neutral position. Further objects are to provide means actuated by the movement of the locking mechanism, for automatically holding the self-starting mechanism against operation, and also rendering the ignition system inoperative, when the transmission mechanism is in the locked condition.

The invention consists in certain novel features and details of construction and arrangement by which the above objects are attained, to be hereinafter described and claimed.

The accompanying drawings form a part of this specification and show a preferred form of the invention.

Figure 1 is a vertical section through a portion of a car, showing the locking mechanism and its operating means in side elevation.

Figure 2 is a vertical section, on a larger scale, through the instrument board and the lock-operating means mounted thereon.

Figure 3 is an elevation of the parts exposed on the face of the instrument board.

Figure 4 is a plan view of the spindle or stem for operating the lock.

Figure 5 is a longitudinal section of such stem, taken on the line 5—5 in Figure 4.

Figure 6 is a transverse section on the line 6—6 in Figure 4.

Figure 7 is a transverse section through the stem on the line 7—7 in Figure 4, showing also the rear face of a dial engaged therewith.

Figure 8 is a plan view of a portion of the transmission case and the locking mechanism thereon, partly in horizontal section.

Figure 9 is a corresponding plan view of a portion with certain parts omitted.

Figure 10 is a vertical section through the lock and adjacent parts, taken on the line 10—10 in Figure 9, and partly in elevation.

Figure 11 is a vertical section through the lock, taken on the line 11—11 in Figure 10.

Figures 12, 13 and 14 are vertical sections, partly in elevation, taken respectively on

the lines 12—12, 13—13 and 14—14 in Figure 9.

Figure 15 is an elevation showing a portion of the lock.

Figure 16 is a plan view showing the under face of a portion of the lock.

Similar reference numerals indicate the same parts in all the figures.

The transmission case 17, see Figures 1 and 8 to 14, has a plate 18 forming part thereof and provided with a vertical cylindrical case or cup 19 containing the mechanism of the lock, which briefly described, comprises a fixed stud 20 having a notched fin 21 and a longitudinally slotted sleeve 22 capable of sliding axially on the stud with its slit engaged with the fin. Notched locking disks 23 are rotatably mounted on the sleeve, held separated by washers 24 fixed on the sleeve, adapted in one position to present their notches to the fin 21 and permit the sleeve to slide vertically upon the stud 20, and in other positions to engage the notches of the fin and prevent such movement; the latter is the locked position. Pins 25 carried by the locking disks 23 are arranged to strike and thus engage adjacent disks and rotate them to assume the unlocked positions when properly manipulated.

On the lower end of the sleeve is an annular flange 26 carrying two oppositely located downwardly projecting spurs 27 moving vertically through openings in the plate 18 and into the case 17 where, in the depressed position, they enter cavities formed in the shifting shafts 28 and hold the latter in the neutral position when the sleeve 22 is lowered and locked, thus holding the car in the inoperative condition.

The lock is arranged to be raised and lowered in the cup 19 by raising and lowering a short vertical shaft 29 extending through the cover 30 of the cup and having a flange 31 rotatably engaged with the sleeve 22 and its disks. Rotating the shaft 29 in the proper directions locks or unlocks the sleeve and stud, and vertical movements of the short shaft 29 lowers or raises the sleeve and its connections to engage or disengage the shifting shafts 28.

These movements are communicated by means of a flexible shaft 32 inclosed in a flexible casing 33 removably fastened at the lower end to the cover 30 of the cup, with the inclosed flexible shaft 32 engaged with

the short shaft 29 at 34. Thus arranged any turning movements of the flexible shaft 32 are communicated directly to the lock mechanism within the cup 19 to rotate the disks 23 to the desired relative positions, and any endwise movements of the flexible shaft 32 raise or lower the sleeve 22 and its connections when the sleeve is in the unlocked condition, correspondingly moving the spurs 27 relatively to the shifting shafts to release or engage the latter.

The upper end of the flexible shaft 32 and its flexible casing 33 extend to mechanism located on the instrument board 35 by which 15 the locking mechanism is operated. On the outer face of the instrument board is a circular plate 36 having a window 37, and a central aperture through which extends a cylindrical dial stem 38. The stem is 20 closed and guided in a tube 39 secured at one end to a plate 40 on the inner face of the instrument board and at the other end to the flexible casing 33 of the flexible shaft 32.

25 The tube 39 is separably fastened to the plate 40 by a screw coupling 41 engaging both the tube and a ring 42 between which the plate 40 is firmly clamped. In the space between the plates 36 and 40 and within 30 an aperture in the instrument board is located the dial 43 mounted on the stem 38 to turn therewith but maintain its position close to the window 37 through which its numerals may be read, while permitting the 35 stem to move axially through the dial. This is accomplished by a tooth 44 projecting into the central hole in the dial, engaged in a longitudinal groove 45 on the stem. Thus arranged the stem 38 may be thrust axially 40 inwardly and outwardly relatively to the instrument board and the dial 43 and to rotate the latter by manipulating the head or button 46 on the outer end of the stem.

45 The opposite end of the stem 38 is drilled and notched to receive and hold firmly the upper end of the flexible shaft 32, as at 47 in Figures 4 and 5. By turning the stem 38 in the proper directions as required by the setting of the locking mechanism and 50 indicated by the presentation of the corresponding numbers at the window 37, the flexible shaft is correspondingly rotated and the movements communicated to the short shaft 29 and the disks 23; the sleeve 22 is thus freed by the unlocking operation and by an outward pull on the head 46 of the stem 38, through the flexible shaft 32, the sleeve is raised and the spurs 27 withdrawn from the shifting shafts 28.

55 In this condition the car may be operated, and to insure against an unintentional inward movement of the stem, due to vibration or other cause, by which the spurs 27 would again lower, a swinging latch 48 is 60 pivotally mounted on the plate 36 adapted

to lie between the plate and head 46 when swung into the engaging position, and thus limit such inward movement.

In order to hold the parts when in the unlocked condition, the stem is grooved longitudinally at 49, see Figures 4, 5 and 6, and an inwardly projecting pin 50 carried by the tube 39 is received in such groove; the latter terminates at its end nearest the head 46 in an annular groove 51 which is 75 presented to the pin 50 when the stem is thrust fully inward to lower the lock and engage the spurs 27 with the shifting shafts 28. In this position the stem may be freely turned to rotate the disks 23 and lock the 80 car. At the opposite end the groove 49 flows into a segmental groove 52 in which the pin is received when the stem is fully withdrawn and the shifting shafts freed. The segmental groove 52 permits sufficient 85 rotary movement of the stem and flexible shaft to insure the proper positioning of the disks 23 relatively to each other when in the unlocked condition. The groove 49 should coincide with a known numeral on 90 the dial to facilitate the axial movement of the stem by proper setting. When in the unlocked condition with the head 46 of the stem in contact with the latch 48 the pin 50 will lie in the groove 49 and hold the 95 stem against rotation.

The combination of numbers to which the lock is set may be changed at will by removing a master pin 53 from its hole in the flange 31, see Figure 16, and reinserting it 100 in any of the several holes 54 provided for the purpose, thus correspondingly changing the entire combination.

As additional safeguards against unauthorized operation of the car, means are 105 provided, operated by the vertical movements of the lock, for making and breaking the electric ignition circuit and for rendering the self-starting system operative or inoperative. These functions are performed 110 through the medium of a control shaft 55 extending through the margin of the cup 19 near its base and having an arm 56 loosely engaged between bars 57 in a recess 58 in the under face of the flange 26 of the 115 sleeve 22. The raising or lowering movements of the flange are thus transmitted to the shaft 55 and cause it to oscillate.

Exterior to the cup 19 on one side thereof is a two-armed knife switch 59 mounted 120 on the control shaft 55 and arranged when the flange 26 is raised to unlock the shifting shafts, to engage the leaves of the contact points 60 and complete the ignition circuit and when the flange is lowered to break 125 such contacts.

On the opposite side of the cup adjacent the starter pedal 61, the overhung end of the control shaft 55 carries a finger 62, see Figures 9, 10 and 14, arranged to strike and 130

travel along the inclined or cam surfaces 63 and 64 on a lever 65 mounted to swing horizontally and having a forked block 66 on one end arranged in one position of the lever to lie beneath the pedal 61 and prevent its depression to close the starter switch, indicated at 67, and in the other position to retract the block as shown in Figure 9 and permit such depression.

10 The above described ignition switch, starter mechanism and control shaft are inclosed in casings 68 and 69 which are shown as removably mounted to slide in ways 70 on the plate 18.

15 Modifications may be made in the forms and proportions of the several mechanisms without departing from the principle of the invention or sacrificing its advantages, and parts may be used without the whole. Although the invention is shown and described as applied to locking the shifting shafts of an automobile, it will be understood that it will serve successfully in other situations to which it may be adapted.

20 25 I claim:—

1. In a motor vehicle, transmission mechanism having shifting shafts, a vertically movable rotatably actuated lock arranged to engage said shifting shafts, a flexible shaft adapted to actuate said lock by rotary movements of said flexible shaft, and to raise and lower said lock by bodily lengthwise non-rotating movements solely of said flexible shaft, and means on the instrument board of such vehicle for operating said flexible shaft.

2. In a motor vehicle, transmission mechanism having shifting shafts, a lock having locking members actuated by rotation, vertically movable means operated by said lock for engaging said shifting shafts, and a flexible shaft adapted for rotation to actuate said members and for bodily lengthwise movement solely to raise and lower said means.

3. In a motor vehicle, transmission mechanism having shifting shafts, a lock having locking members actuated by rotation, vertically movable means operated by said lock for engaging said shifting shafts, a flexible shaft adapted for rotation to rotate and actuate said members, and to move bodily lengthwise solely to raise and lower said means, and a rotatable stem mounted to slide axially on the instrument board of such vehicle and joined to said flexible shaft.

4. In a motor vehicle, transmission mechanism having shifting shafts, a lock having locking members actuated by rotation, vertically movable means operated by said lock for engaging said shifting shafts, a flexible

shaft adapted for rotation to rotate and actuate said members, and to move bodily lengthwise only to raise and lower said means, a rotatable stem mounted to slide axially on the instrument board of such vehicle and connected to said flexible shaft, and movable means for limiting the inward axial movement of said stem.

5. In a motor vehicle, transmission mechanism having shifting shafts, a lock having locking members actuated by rotation, vertically movable means operated by said lock for engaging said shifting shafts, a flexible shaft adapted for rotation to rotate and actuate said members, and to move bodily lengthwise solely to raise and lower said means, a rotatable stem mounted to slide axially on the instrument board of such vehicle and connected to said flexible shaft, a head on said stem, and a movable latch between said head and instrument board.

6. In a motor vehicle, transmission mechanism having shifting shafts, a lock having locking members actuated by rotation, vertically movable means operated by said lock for engaging said shifting shafts, a flexible shaft adapted to rotate and actuate said members, and to move bodily lengthwise to raise and lower said means, a rotatable stem mounted in a guide on the instrument board of such vehicle, and having an annular groove and a connecting longitudinal groove, and a pin in said guide projecting into and coacting with said grooves, said stem connected to said flexible shaft.

7. In a motor vehicle, transmission mechanism having shifting shafts, a lock having locking members actuated by rotation, vertically movable means operated by said lock for engaging said shifting shafts, a flexible shaft adapted for rotation to rotate and actuate said members, and to move bodily lengthwise solely to raise and lower said means, and a switch automatically operated by said vertically movable means.

8. In a motor vehicle, transmission mechanism having shifting shafts, a vertically movable lock arranged to engage said shifting shafts by a lowering movement and to release said shifting shafts by a rising movement, a control shaft oscillated by such movements of said lock, an ignition switch automatically operated by the oscillations of said control shaft, and a starting switch automatically operated by the oscillations of said control shaft, said switches arranged to be held in inoperative positions when said shifting shafts are engaged by said lock.

In testimony that I claim the invention above set forth I affix my signature hereto.

STEPHEN L. MORGAN.
